UNITED STATES PATENT OFFICE.

ARTHUR DICKERSON, OF SALT LAKE CITY, UTAH, ASSIGNOR, BY DIRECT AND MESNE ASSIGNMENTS, TO DICKERSON ENGINE COMPANY, A CORPORATION OF UTAH.

INTERNAL-COMBUSTION ENGINE.

1,304,744.

Specification of Letters Patent. Patented May 27, 1919.

Application filed May 22, 1918. Serial No. 236,031.

To all whom it may concern:

Be it known that I, ARTHUR DICKERSON, a citizen of the United States, residing at Salt Lake City, in the county of Salt Lake 5 and State of Utah, have invented certain new and useful Improvements in Internal-Combustion Engines, of which the following is a specification.

My invention relates to internal combustion engines, and has for its object to provide a compact, multiple cylinder engine in which the cylinders are constructed by bolting duplicate sides together and on which a single rotary valve regulates the intake and 15 exhaust ports of all of the cylinders.

These objects I accomplish with the device illustrated in the accompanying drawings in which similar letters and numerals of reference indicate like parts throughout 20 the several figures and as described in the specification forming a part of this application and pointed out in the appended claims.

In the drawings in which I have shown a 25 substantial embodiment of my invention Figure 1 is an end view in elevation of the engine, with parts shown in vertical section. Fig. 2 is a vertical longitudinal section through the engine showing a portion 30 of the inside of the cylinder case, one piston, and connection rod in elevation, and a portion of the valve case, one piston and portions of the crank shaft in section. Fig. 3 is a view in perspective of the valve case, 35 valve shaft and manifold with portions cut away. Fig. 4 is a plan view of the lower or bottom portion of the valve case. Fig. 5 is a transverse section of the same. Fig. 6 is an inverted plan view of the top or upper 40 portion of the valve case. Fig. 7 is a transverse section of the same. Fig. 8 is an elevation of the valve shaft showing the relative position of the ports therein some of which are shown in dotted lines. Fig. 9 is 45 a transverse section of the valve case and valve showing the relative sizes of the ports. Fig. 10 is a view in transverse section showing the valve shaft in the position when the ports are just opening to exhaust.

50 The engine shown has four cylinders, A, B, C and D, which are formed by bolting two coacting sides 1 and 2 together within each of which are formed semi-cylindrical recesses or openings constituting one-half of 55 the said cylinders, A, B, C and D and one-

half of the crank case E. The crank shaft F is mounted in said crank case E with suitable bearings 3. The outer side of each of said cylinder sides 1 and 2 forms one or more of the walls of the water jacket G 60 which is formed by bolting the plates 4 on extended flanges of the sides 1 and 2 and adjacent said cylinders A, B, C and D. A sprocket wheel 5 is secured on one end portion of said crank shaft, and another 65 sprocket wheel 6 is secured on the end portion of the valve shaft 7. A chain belt 8 connects the said crank shaft and valve shaft whereby the motion of said crank shaft is imparted to said valve shaft 7. Pistons are operated in the respective cylinders and connected with the said crank shaft F. The valve case H is constructed by bolting four plates together and rigidly upon the upper end of the cylinders A, B, 70 C and D and as a closure for said cylinders, and a bearing for said valve shaft 7. Two of said plates, shown at 9 and 10 are semi-cylindrically recessed on their abutting faces as at J to form the bearings for said valve shaft 7 and are also longitudinally recessed on their outer faces to form a water jacket 13 for the valve shaft. The water jacket 13 is completed by the outer plates 11 and 12 when the said four plates 75 are bolted together and in place on the said sides 1 and 2, and connected with the cylinder water jacket G by conduits leading from one to the other. Intake ports 14 are provided to introduce the exploding gas to 80 each cylinder by recesses cut into and partially across the contiguous faces of said plates 9 and 10 preferably at right angles to the valve shaft recess J and horizontally disposed. Exhaust ports 15 are likewise 85 provided leading from said valve shaft recess at right angles thereto and horizontally disposed, to the opposed side of said valve case H. Ports 16 are cut vertically through said plates 10 and 11 connecting said valve 90 shaft recess J with the respective cylinders A, B, C and D and are wider than ports 14 or 15. A tubular intake casing 17 is provided connecting all of said intake ports 14 with the carburetor of the engine, which is 95 not shown, to form the intake manifold, and on the opposite side of said valve casing H a similar casing 18 is provided connecting all of said exhaust ports 15 to form 100 the exhaust manifold. An oil pipe 19 is 105 connected with the carburetor of the engine, which is not shown, to form the oil manifold, and on the opposite side of said valve casing H a similar casing 18 is provided connecting all of said exhaust ports 15 to form 110 the exhaust manifold. An oil pipe 19 is

provided leading from the said crank case E to an oil case 20 which is secured on the top of the said plates 12, and oil conduits 21 are bored through the said plates 9 and 12 connecting said oil case 20 with the said valve shaft recess J for lubrication of the valve shaft 7. The said conduits 21 are bored semi-spherical at their lower end to form a seat for ball valves, 22 which are carried in said conduits, said ball valves control the flow of oil from the said case 20 to the valve shaft 7.

I thus provide a splash system of oiling for the crank shaft and connections with impulses imparted to the oil carried in said crank case to force some of said oil through the said pipe 19 and supply the required oil in the said oil case 20. The commonly used spark plugs 24 are to be screwed into openings 25 leading to the interior of said cylinders near their top for firing the gas compressed in said cylinders by their respective pistons 23. The said valve shaft 7 is a solid metal shaft with portions thereof cut out to form the ports 26, one of which is provided for each cylinder, and in longitudinal alinement with the said ports 14, 15 and 16 and adapted to be brought into operative transverse alinement with two of said ports 25 according to the rotation of said valve shaft and the particular cylinder to be fired. And to be more specific a segment of said shaft 7 is cut away for each cylinder of such portions of the shaft as will leave the ports 14 and 15 closed when the contiguous port 26 is parallel with the valve case II, see Fig. 9. And when the said valve shaft is in operative position it will be in longitudinal alinement with said ports 14, 15 and 16, 40 and, with the cords of the segments so positioned relative to each other and the said ports 14, 15 and 16 as to bring a desired intake port 14 and its adjacent port 16 into connection with one of said ports 26, to 45 form an intake gas conduit for that particular cylinder, while one of the other of said ports 26 will be in connection with an exhaust port 15 and its adjacent port 16 to form an exhaust conduit for exploded gas 50 from one of the other cylinders, and at the same time the other ports 26 will be closed, that is, the uncut portion of said valve shaft will close the ports 14, 15 and 16 of the other cylinders. The object of cutting out a segment 55 of the shaft to form the ports 26 rather than to form said ports entirely within the shaft is to provide less material in the shaft at that particular point to release the expansion of that portion of the shaft which occurs when that portion of the shaft closes the said port 16 at the instant of firing, as well as to receive the cooling effect when used in the intake position, also to provide quicker and freer action through the ports. 60 A collar 27 having a cam groove 28 cut

therein is secured on said valve shaft 7, and a U-shaped spring 29 is secured to said plate 12. A roller 30 is journaled on the end of said U-shaped spring 29 to operate in said cam groove 28 whereby said valve shaft 7 is made to reciprocate longitudinally. The said spring 28 allowing less reciprocation of the said shaft when the shaft is made to rotate rapidly than when rotating slowly.

The operation of my invention is as follows:

With the parts of the engine in the position shown in Fig. 2, the piston 23 in the cylinder A is ready to draw in the gas and the piston in the cylinder B is ready to exhaust through the ports 16, 26 and 15, when the crank shaft F is rotated. By firing the gas as described in one of the other cylinders for instance D, the crank shaft will be rotated and cylinder A will be filled with gas from the intake manifold 17 through the ports 14, 26 and 16, while the exploded gas in cylinder B will be driven out as the exhaust therefrom, through the exhaust manifold 18, and the gas in cylinder C will be compressed. In the meantime the valve shaft is being rotated by the chains 8 and as the said ports 26 are large enough to remain practically open until the respective pistons have traveled practically their full throw and then they close quickly which allows free flow of the gas, and as the said crank shaft F is given two rotations on its axis while the valve shaft 7 is rotated once, when the piston in cylinder D is moved downward by said explosion the pistons in B and C will be moved upward, the cylinder B to exhaust and the cylinder C to compress a charge of gas and instantly thereafter to fire it.

The collar 27 with the cam groove 28 therearound when moved by an element operable in said groove will cause said valve shaft 7 to reciprocate when it is rotated, and my improvement is in providing a spring element as shown in the U-shaped spring 29 with the roller 30 engaging in said cam groove 28, whereby, when the said valve shaft is slowly rotated its reciprocations will be the full throw of said groove, but when said shaft is rotated rapidly the said spring and cam will yield relatively one to the other as the rotations of said shaft are increased and decreased, and by that means distribute the lubrication without the usual scoring of said shaft from lack of oil and wear. As said valve shaft is rotated the said ports 26 allow the said balls 22 to remain in their seats and when the uncut portions of said valve shaft are brought into engagement or contact with said balls they are raised out of their seats and oil will flow through the conduits 21 for lubricating the shaft.

I thus provide an economical and efficient

construction for the crank case and water jacket for internal combustion engines, cylinder for the same which may be quickly repaired by shaving the contiguous faces 5 of the sides forming the cylinders, together with a yieldingly reciprocating rotary valve thereon with a case and coacting ports by which expansion of the parts is eliminated, the passage and control of the gases is accurate, rapid and positive, and all wearing 10 parts of which may be oiled by novel lubricating means.

Having thus described my invention I desire to secure by Letters Patent and claim:—

- 16 1. An internal combustion engine consisting of duplicate plates bolted together and recessed to form spaced apart explosion cylinders and a crank case at one end of said cylinders; a crank shaft mounted in 20 said crank case; pistons operable in said cylinders and connected with said crank shaft; coacting recessed plates bolted together and to the end of said duplicate plates to form a closure for said cylinders, 25 and provided with ports opening into said cylinders; a yieldingly reciprocating rotary valve shaft operable in one of the recesses in said second mentioned plates having segment portions cut away to form ports 30 adapted to coact with the ports in said plates; and means to conduct explosive gas to the ports in said plates with means to fire said gas when compressed in said cylinders.
- 35 2. An internal combustion engine comprising a rotary valve shaft having segment portions cut out to form ports therein; a casing for said valve shaft having ports formed therein adapted to coact with the 40 ports in said shaft; a collar having a cam groove cut therein secured on said valve shaft; and a spring secured to said casing and a portion of which is operatively connected with said collar to dampen the action 45 of the cam groove and shorten the endwise movements of said valve shaft when said shaft is rapidly rotated and lengthen said movements when said shaft is rotated slower.
- 50 3. An internal combustion engine consisting of duplicate plates bolted together and recessed to form spaced apart explosion cylinders and a crank case at one end of said cylinders; a crank shaft mounted in 55 said crank case; pistons operable in said cylinders and connected with said crank shaft; coacting recessed plates bolted together and to the end of said duplicate plates to form a closure for said cylinders, 60 and provided with ports opening into said cylinders and oil conduits bored to form valve seats; a yieldingly reciprocating rotary valve shaft operable in one of the recesses in said second mentioned plates having segment portions cut away to form 65

ports adapted to coact with the ports in said plates, ball valves in said oil conduits to be operated by said rotary valve shaft; means to conduct explosive gas to the ports in said plates with means to fire said gas 70 when compressed in said cylinders; and an oil pipe connecting each crank case with said oil conduits.

4. An internal combustion engine comprising a rotary valve shaft having segment portions cut out to form ports therein; a casing for said valve shaft having ports formed therein adapted to coact with the ports in said shaft and oil conduits to form valve seats; ball valves adapted to 80 operate in said conduits by said valve shaft; a collar having a cam groove cut therein secured on said valve shaft, and a spring secured to said casing and a portion of which is operatively connected with said 85 collar to dampen the action of said cam groove and shorten the endwise movements of said valve shaft when said shaft is rapidly rotated and lengthen said movements when said shaft is rotated slower. 90

5. An internal combustion engine consisting of duplicate plates bolted together and recessed to form spaced apart explosion cylinders and a crank case at one end of said cylinders; a crank shaft mounted in said 95 crank case; pistons operable in said cylinders and connected with said crank shaft; coacting recessed plates bolted together and to the end of said duplicate plates to form a closure for said cylinders, and provided 100 with ports, and with oil conduits opening into said cylinders; ball valves operable in said conduits; a yieldingly reciprocating rotary valve shaft operable in one of the recesses in said second mentioned plates 105 having segment portions cut away to form ports adapted to coact with the ports in said plates and operate said ball valves; and means to conduct explosive gas to the ports in said plates with means to fire said gas 110 when compressed in said cylinders.

6. An internal combustion engine comprising a rotary valve shaft having segment portions cut out to form ports therein; a casing for said valve shaft having ports formed therein adapted to coact with the ports in said shaft and oil conduits; ball valves in said oil conduits operated by said rotary valve shaft; a collar having a cam groove cut therein secured on said valve 115 shaft; and a spring secured to said casing with a portion operatively connected with said collar to dampen the action of said cam groove and shorten the endwise movements of said valve shaft when said shaft is rapidly 120 rotated and lengthen said movements when said shaft is rotated slower.

7. An internal combustion engine consisting of duplicate plates bolted together and recessed to form spaced apart explosion 125

cylinders and a crank case and an oil case at one end of said cylinders; a crank shaft mounted in said crank case; pistons operable in said cylinders and connected with said 5 crank shaft; coacting recessed plates bolted together and to the end of said duplicate plates to form a closure for said cylinders, and provided with ports opening into said cylinders and having oil conduits bored 10 therein; ball valves in said oil conduit; a yieldingly reciprocating rotary valve shaft operable in one of the recesses in said second mentioned plates having segment portions cut away to form ports adapted to 15 coact with the ports in said plates and operate said ball valves; means to conduct explosive gas to the ports in said plates with means to fire said gas when compressed in said cylinders; and an oil pipe connecting 20 said oil case and said oil conduits.

8. An internal combustion engine comprising a rotary valve casing having alined ports formed therein and a larger adjacent port at right angles to said alined ports 25 adapted to coact with the ports of a rotary valve journaled in said casing; a yieldingly reciprocating rotary valve with segment portions cut out to form ports adapted to coact with either of said alined ports and its

adjacent right angled port; an oil casing on 30 said valve casing with oil conduits therein and valves in said conduits adapted to be operated by said rotary valve shaft; a collar having a cam groove cut therein secured on said valve shaft; and a spring secured to 35 said casing and a portion of which is operatively connected with said collar to dampen the action of said cam groove and shorten the endwise movements of said valve shaft when said shaft is rapidly rotated and 40 lengthen said movements when said shaft is rotated slower.

9. An internal combustion engine comprising a rotary valve shaft having ports 45 therein for the passage of gas; a casing having ports adapted to coact with the ports in the valve shaft; a cam for reciprocating the valve shaft; a spring to variably dampen the action of the cam; oil conduits with valve seats therein leading through the casing to the valve shaft in line with the ports therin; and valves in the oil conduits which are adapted to be lifted from their 50 seats when the body of the valve shaft is opposite the outlets of the oil conduits. 55

In testimony whereof I have affixed my signature.

ARTHUR DICKERSON.
